(57) **CLAIM**

The ornamental design for a cervical collar, as shown and described.

DESCRIPTION

FIG. 1 is a perspective view of an embodiment of a lower portion in an anterior component for a cervical collar.

FIG. 2 is a front elevational view according to FIG. 1.

FIG. 3 is a rear elevational view according to FIG. 1.

FIG. 4 is a top plan view according to FIG. 1.

FIG. 5 is a bottom plan view according to FIG. 1.

FIG. 6 is a first side elevational view according to FIG. 1; and,

FIG. 7 is a second side elevational view according to FIG. 1.

The evenly dashed broken lines depict portions of the cervical collar and form no part of the claim. The dash dot dash lines depict a claim boundary and form no part of the claim.

1 Claim, 7 Drawing Sheets
